Patented May 10, 1921.

Alfred Rozowsky Inventor
By his Attorney Sigmund Hayog

UNITED STATES PATENT OFFICE.

ALFRED ROZOWSKY, OF NEW YORK, N. Y.

DESIGN FOR A CANDY-PACKAGE.

57,864.

Specification for Design.

Patented May 10, 1921.

Application filed November 10, 1919. Serial No. 337,033. Term of patent 3½ years.

To all whom it may concern:

Be it known that I, ALFRED Rozowsky, a citizen of the United States, residing at New York, in the county of Kings and State of New York, have invented a new, original, and ornamental Design for Candy Packages, of which the following is a specification, reference being had to the accompanying drawing, forming part thereof.

The figure is a perspective view of a candy package, showing my new design.

I claim:—

The ornamental design for a candy package, as shown.

ALFRED ROZOWSKY.
